CLAIM

The ornamental design for a cooking apparatus socket part, as shown and described.

DESCRIPTION

FIG. 1 is a top-front-right perspective view of a cooking apparatus socket part, showing the design;

FIG. 2 is a bottom-front-left perspective view of the cooking apparatus socket part of FIG. 1;

FIG. 3 is a top-rear-left perspective view of the cooking apparatus socket part of FIG. 1;

FIG. 4 is a bottom-rear-right perspective view of the cooking apparatus socket part of FIG. 1;

FIG. 5 is a rear view of the cooking apparatus socket part of FIG. 1;

FIG. 6 is a left view of the cooking apparatus socket part of FIG. 1;

FIG. 7 is a top view of the cooking apparatus socket part of FIG. 1;

FIG. 8 is a right view of the cooking apparatus socket part of FIG. 1;

FIG. 9 is a bottom view of the cooking apparatus socket part of FIG. 1; and,

FIG. 10 is a front view of the cooking apparatus socket part of FIG. 1.

The broken lines in the drawings illustrate environmental subject matter that forms no part of the claimed design.

1 Claim, 10 Drawing Sheets
